PAPER BAG

Ralph L. Bangs, Wakefield, and William A. Hermanson, Brighton, Mass., assignors to Forest Wadding Company, Boston, Mass.

Application July 24, 1931, Serial No. 552,944

3 Claims. (Cl. 229—53)

The present invention relates to a bag and more particularly to a bag adapted to carry either hot or cold bodies and preserve the degree of heat or cold for some time.

5 Food stuffs in cold or hot state are frequently shipped in containers of a more or less permanent nature. Usually ordinary ice or dry ice is used to keep the food stuff cool, and this may be done by packing the ice around the food or by 10 putting the dry ice in a container within the container holding the food. Packing of this nature applies more often for bulk shipment or shipment in large quantity. Very little attention has been paid to the ordinary vending of 15 hot or cold food stuff where the customer takes the package home with him, and usually no provision is made to keep the food at its original temperature.

The object of this invention is to provide an 20 inexpensive paper bag suitably made and capable of keeping whatever may be put in it, at or near the original temperature. The bag may be used to keep ice cream, or it may be used to keep foods hot, as cooked meats, for instance. It may 25 be used for warm lunches if desired at picnics etc., or for any purpose.

The bag is constructed in such a way, that when it is closed it is completely sealed and provides also a completely sealed heat insulating 30 batting about the material contained therein. The insulation of the bag has been particularly prepared in connection with the bag itself and provides such an efficient type of insulation that the temperature, if the bag is pre-heated or 35 cooled, as the case may be, of the food practically remains the same for a number of hours.

The nature of the invention and its advantages and uses will be more fully discussed and explained in connection with the embodiment of 40 the same described in the specification and shown in the drawing.

In the drawing, Figure 1 shows a front view of the bag; Figure 2 shows a section taken on the line 2—2 in Figure 1; Figure 3 shows a section 45 taken on the line 3—3 of Figure 1; Figure 4 shows an enlarged section taken through a small part of the wall of the bag on the line 4—4 where the insulation is; Figure 5 shows the bag, somewhat in perspective as used; and Figure 6 shows a 50 modification of the structure shown in Figure 3.

The bag is composed of an outer and inner 55 paper cover numbered 1 and 2 respectively. At the top open end portion of the bag, these covers are joined together by means of latex or other equivalent substance as indicated more clearly in

Figure 2, and this joining extends downward to the point where the batting 3 is inserted between the outer and inner cover. The batting 3 may have on the inner side of it a second batting 4, of a thinner and slightly different construction, as will be explained later and this second batting may not extend up as far as the first so as to make a more gradual slope to the point where the inner and outer sheets are joined.

While we have used batting in many cases, a 10 wadding of the same composition as the batting but having a top and bottom sheet formed by a sizing impregnating the top and bottom fibres may be used.

The batting as indicated above is preferably 15 applied in two layers, the thicker outer layer having paper covers 5, 5 at each side, and itself composed of one or more layers of batting having a mixture of absorbent cotton fibres, rubberized fibres, and jute. The outer paper covers may be 20 of water or moisture proof material, but preferably are plain flexible paper of suitable texture and pliability. Asphaltum sheets may be used as a cover of the batting or in addition to the paper cover, and preferably would be placed next 25 to the batting itself in case other paper was also used.

The batting 3 extends about the sides of the bag as one continuous piece and has the inner paper covers joined with latex at 6 as indicated 30 in Figure 3 though the inner paper may cut short on the sides as indicated in Figure 6 and the latex or other suitable material used to join the batting proper itself and the outer paper cover. In this way the ends of the batting are sealed as 35 indicated in Figures 3 and 6 and prevent any conduction or convection directly through the paper covers of the bag.

The inner batting 4 has a heavier outer and inner paper cover than the batting 3 and tends 40 to provide in part a form on which the outer batting can fit. The covers 7, 7, of the inner batting may be stronger than the outer batting papers if desired.

In place of making the batting or wadding as 45 described above, the insulating material may be of cellulose wood pulp made in creped webbed sheets having a soft nap and laid together or the wood pulp may be shredded in fibre form and 50 made as batting or wadding.

At the top edge of the bag on one side is a tab or strip 8, having a metallic strip 9 inserted therein, and extending beyond the side edges of the bag. This strip is folded over the open end of 55

the bag after the contents are put in, and then rolled down to the point where the batting begins. The extended edges can then be folded about the edge of the bag to keep the bag closed properly.

5 As indicated in Figure 5, a handle 10 may be riveted or otherwise affixed to the side of the bag, but the top folded over may also serve for this purpose and the handle omitted if desired.

Having now described our invention, we claim:

10 1. A paper bag comprising an inner and outer cover, a heavy insulating batting extending about the sides and bottom of said bag, means for joining the edges of said batting, a second lighter layer of batting adjoining the inner side of said 15 first layer, said second layer having a paper cover on the inner side thereof.

2. A paper bag comprising an inner and an outer cover formed as separated elements and united in face to face relation only about the entire upper open end portion, the covers being otherwise free, an insulated layer of wadding positioned within the covers and extending about the closed lower end of the bag, the edges of the wadding at the sides coming together to completely enclose the inner bag.

3. A paper bag of the flat envelope type comprising an inner and an outer cover formed as separated elements and united in face to face relation only about the entire upper open end portion, the covers being otherwise free, an insulated layer of wadding positioned within the covers and extending about the closed lower end of the bag, the edges of the wadding substantially coming together at the sides and making a complete enclosure of the inner bag when the bag is filled. 10 15
